RECEIVING APPARATUS FOR COMMUNICATION SYSTEMS

Willard P. Place, Wilkinsburg, Pa., assignor to
The Union Switch & Signal Company, Swiss-
vale, Pa., a corporation of Pennsylvania

Application March 26, 1937, Serial No. 133,214

12 Claims. (Cl. 179—82)

My invention relates to receiving apparatus for communication systems, and particularly to receiving apparatus for communication systems operating on the closed circuit principle.

5 I shall describe one form of apparatus embodying my invention, and shall then point out the novel features thereof in claims.

A feature of my invention is the provision of 10 novel and improved receiving apparatus for communication systems which operate on the closed circuit principle by virtue of a signaling current of a predetermined characteristic normally flowing in the transmitting circuit for continuously indicating during non-communicating periods that 15 the system is in working order. Other features and advantages of my invention will appear as the specification progresses.

Receiving apparatus constructed in accordance 20 with my invention is normally conditioned for reception and is responsive to signaling current of a predetermined frequency for actuating an indicator, and the apparatus is automatically conditioned for reproducing the voice frequencies of a telephone current when such signaling current 25 ceases. Discontinuance of the display of the indicator when not immediately followed by reception of a telephone message is a warning of a failure of the system.

Apparatus embodying my invention is especially 30 useful for communication systems for railway trains where the movements of a train are governed in part, at least, in accordance with verbal instructions received aboard a vehicle of the train from a remote station, the communication current 35 being transferred to such vehicle through the medium of train carried elements effectively coupled with wayside circuits. Preferably, the communication current is picked up by the train carried apparatus by virtue of an inductor 40 mounted on a vehicle of the train in inductive relation with the track rails, the track rails being included in a wayside transmitting circuit. It will be understood, however, that my invention is not limited in its use to communication systems 45 for railway trains, and many places will suggest themselves where the apparatus will be useful.

For a better understanding of my invention, reference may be had to the accompanying drawing, 50 which is a diagrammatic view of one form of apparatus embodying the invention.

Referring to the drawing, the receiving equipment normally conditioned for reception comprises an inductor coil IC, a filter BPF and an 55 amplifier-demodulator AD. The inductor coil IC

is disposed for inductive relationship with a transmitting circuit, not shown. When the apparatus is installed on a vehicle of a railway train, the inductor coil IC preferably is mounted on the vehicle in inductive relation with the track rails. 5 The electromotive forces induced in the inductor coil IC in response to current flowing in the associated transmitting circuit are applied over wires 2 and 3 to the input side of the filter BPF, the output side of which filter is connected over 10 wires 5 and 6 with the input terminals of the amplifier-demodulator AD. A circuit controlling contact 4, to be referred to later, may be interposed in the wire 3. The filter BPF is of the usual band-pass type and is proportioned and adjusted 15 to pass the frequency band of the communication current and to substantially suppress frequencies either above or below such band. For example, it has been proposed in communication systems for railway trains to employ the upper side band 20 of a carrier current of 7000 cycles per second modulated with voice frequencies for telephone communication, and to use the equivalent of such carrier current modulated by a single predetermined voice frequency for signaling. Under such 25 circumstances, the filter BPF would pass a band extending from 7500 to 9500 cycles, the voice frequency range being taken as extending from 500 30 cycles to 2500 cycles. For signaling, the current may be that of 7800 cycles, which is the equivalent 35 of the upper side band of the carrier of 7000 cycles modulated by the voice frequency of 800 40 cycles.

The amplifier-demodulator AD may be any one 45 of several well-known types for such devices, and is shown conventionally only for the sake of simplicity. It is deemed sufficient for this application to point out that the amplifier-demodulator AD includes a normally active source of carrier current for mixing with the incoming communication current, and is operative to cause only the voice frequencies to appear in the output circuit of the demodulator, the local carrier and the other products of demodulation being suppressed and not appearing in the output circuit. On the 50 assumption the communication current is of the frequencies referred to hereinbefore, then the voice band of frequencies extending from 500 to 2500 cycles per second would appear in the output circuit of the demodulator when telephone current is picked up by the inductor coil IC, and the single predetermined frequency of 800 cycles per second would appear in the output circuit when signaling current is picked up by the inductor coil IC. 55

The amplifier-demodulator AD is provided with a normally closed output circuit including a resonant circuit and a winding operatively associated with a loud speaker or telephone receiver. As here shown, the resonant circuit is of the parallel resonant circuit type consisting of an inductor L and a condenser CL connected in parallel, and the winding associated with the loud speaker is the usual voice winding or coil 9 of a loud speaker LS. To form a normally closed output circuit for the amplifier-demodulator, one terminal of the resonant circuit is connected over wire 7 with one output terminal of the amplifier-demodulator AD, and a mid terminal of the inductor L is connected over wire 10, voice coil 9 of loud speaker LS and wire 8 with the other output terminal of the amplifier-demodulator. The resonant circuit consisting of inductor L and condenser CL is proportioned for resonance at the voice frequency corresponding to the predetermined frequency of the signaling current. When the signaling current is of the frequency assumed hereinbefore for the purpose of illustration, the resonant circuit is tuned for resonance at 800 cycles per second. Consequently, a current of relatively large amplitude of 800 cycles per second flows in the output circuit in response to the signaling current picked up by the inductor coil IC and supplied to the amplifier-demodulator. The parts are further so proportioned and the terminal of inductor L, to which wire 10 is connected, is so positioned that the impedance of the output circuit is not large at the voice band of frequencies, and the winding 9 is effectively influenced when the telephone current is picked up by the inductor coil IC and supplied to the amplifier-demodulator.

A portion of the winding of inductor L is connected across the input terminals of a full wave rectifier 11, the output terminals of which are connected with the winding 12 of a relay R. It follows that the relay R is effectively energized by rectified current and picked up in response to the signaling current flowing in the output circuit of the amplifier-demodulator, but that the relay is deenergized and immediately releases when the signaling current ceases.

The relay R controls a first indicator here shown in the form of a lamp 13, a second indicator here shown in the form of a bell 14, and the field winding 15 of the loud speaker LS. The indication lamp 13 is illuminated by current supplied over a simple circuit including the B terminal of any convenient source of current such as a battery not shown, front contact 16 of relay R, lamp 13 and to the C battery terminal. The field winding 15 of the loud speaker LS is energized when relay R is released over a circuit extending from the B terminal, back contact 17 of a continuity transfer 60 contact of relay R, transfer contact 18, wire 19, winding 15 and to the C terminal. The bell 14 is energized momentarily during the release and pick up of relay R, the circuit being closed during the interval the back contact 17 and the front contact 20 are both in engagement with the transfer contact 18, as will be readily understood by an inspection of the drawing.

The operation of the apparatus is as follows. Under normal conditions, that is, during non-telephone periods, signaling current is continuously supplied to the transmitting circuit by apparatus at an associated remote station, and the electromotive force induced in the inductor coil IC is of the frequency corresponding to the frequency of the signaling current. This frequency of the

electromotive force falls within the pass band of the filter BPF, and hence the electromotive force is supplied to the input side of the amplifier-demodulator and causes a current of corresponding frequency to appear in the output circuit of the demodulator, and which latter frequency is the resonant frequency of the resonant circuit consisting of inductor L and condenser CL. Consequently, during reception of signaling current the relay R is effectively energized and picked up by 10 the rectified portion of current passed by the rectifier 11. With the relay R picked up to close front contact 16, the lamp 13 is illuminated to indicate the reception of signaling current. In other words, the lamp 13, when illuminated, indicates that the transmitting circuit and the receiving apparatus are in working order.

When the signaling current is interrupted, the relay R is deenergized and at once releases, the lamp 13 being extinguished when the front contact 16 is opened. During the release of relay R, the bell 14 is sounded when both the back contact 17 and the front contact 20 are in engagement with the transfer contact 18, and the bell audibly indicates the termination of the signaling current. With the relay R fully released to close back contact 17, the field winding 15 of the loud speaker LS is energized and the loud speaker is conditioned for reproduction of the voice frequencies of a current flowing in the 30 voice coil 9. The electromotive forces induced in the inductor coil IC by a telephone current flowing in the transmitting circuit are passed by the filter BPF to the amplifier-demodulator and cause corresponding voice frequencies to appear in the output circuit of the demodulator, with the result that the telephone message is reproduced by the loud speaker LS. At the termination of telephone communication, signaling current is reapplied to the transmitting circuit, the relay R is reenergized and the apparatus is restored to its normal condition. During the pick up of the relay, the bell 14 is again sounded to call attention to the restoring of the apparatus to the normal condition. If no speech follows the extinction of the lamp 13, then the operator would know that the system is out of order and may take whatever steps are necessary. A portion of the winding 12 of relay R is short-circuited over a 50 back contact 21 of the relay and the relay is provided with slow pick-up characteristics. The relay R is preferably slow to pick up so that occasional current of the predetermined voice frequency of the signaling current which may pass through the rectifier to the relay R during reception of telephone current does not energize the relay for a sufficient period to pick up the relay and interrupt the operation of the loud speaker.

It is to be understood that receiving apparatus and transmitting apparatus may be provided at the same station and two-way communication may be carried on. It is understood, of course, that the transmitting apparatus at one station 65 does not interfere with the operation of the receiving apparatus at the same station. This implies different frequencies, different paths for the transmitted and received currents, or any other suitable well-known means. As here shown, the contact 4 would be operated either manually or automatically to render the amplifier-demodulator AD immune to the current transmitted from the same station.

Although specific frequencies have been used 75

in illustrating the invention, it will be understood that the invention is not limited to these frequencies and other frequencies for the communication current may be selected if desired.

5 As a matter of fact, the frequency of the signaling current may be outside of the voice band.

In the foregoing description, I have referred to the signaling current as being used primarily to check that the system is in working order. It is 10 clear that the signaling current may also be used for code signaling by providing apparatus at the remote station effective to periodically interrupt the signaling current in accordance with a prearranged code. Under such circumstances, the 15 relay R and the indicators 13 and 14 would be operated in accordance with the prearranged code.

Although I have herein shown and described only one form of apparatus embodying my invention, it is understood that various changes and modifications may be made therein within the scope of the appended claims without departing 20 from the spirit and scope of my invention.

Having thus described my invention, what I 25 claim is:

1. Receiving apparatus for communication systems comprising, a demodulator capable of demodulating a carrier telephone current and a signaling current equivalent to the carrier modulated by a predetermined frequency, a parallel resonant circuit proportioned for resonance at said predetermined frequency, a loud speaker, a first winding associated with the loud speaker, means to connect said resonant circuit and said first winding across the output terminals of the demodulator to form an output circuit for the demodulator, a relay, means to connect a winding of the relay with said resonant circuit to energize the relay in response to such signaling 30 current supplied to the demodulator, and circuit means including a back contact of the relay and a second winding associated with the loud speaker as well as a current source to condition the loud speaker as required for reproducing the voice frequencies of the current flowing in said first winding in response to such telephone current supplied to the demodulator.

2. Receiving apparatus for communication systems comprising, a demodulator capable of demodulating a carrier telephone current and a signaling current equivalent to the carrier modulated by a predetermined frequency, a parallel resonant circuit proportioned for resonance at said predetermined frequency, a loud speaker, a first winding associated with the loud speaker, means to connect said resonant circuit and said first winding across the output terminals of the demodulator to form an output circuit for the demodulator, a relay, means to connect a winding of the relay with said resonant circuit to energize the relay in response to said signaling current supplied to the demodulator, an indication circuit including an indicator and a front contact of the relay to indicate the reception of signaling current, and other circuit means including a back contact of the relay and a second winding associated with the loud speaker to condition the loud speaker as required for reproducing the voice frequencies of the current flowing in the 60 said first winding in response to said telephone current supplied to the demodulator.

3. Receiving apparatus for communication systems comprising, a demodulator capable of demodulating a carrier telephone current and a signaling current equivalent to the carrier mod-

ulated by a predetermined frequency, a parallel resonant circuit proportioned for resonance at said predetermined frequency, a loud speaker, a first winding associated with the loud speaker, means to connect said resonant circuit and said first winding across the output terminals of the demodulator to form an output circuit for the demodulator, a relay, means to connect a winding of the relay with said resonant circuit to energize the relay in response to said signaling current supplied to the demodulator, an indication circuit including a lamp and a front contact of the relay to indicate the reception of signaling current, another indication circuit including a bell and a contact closed momentarily when the relay is released to indicate when reception of the signaling current ceases, and other circuit means including a back contact of the relay and a field winding of the loud speaker to condition the loud speaker for reproducing the voice frequencies of the current flowing in said first winding in response to reception of said telephone current.

4. Receiving apparatus for communication systems comprising, a demodulator capable of demodulating a carrier telephone current and a signaling current equivalent to the carrier modulated by a predetermined frequency, a parallel resonant circuit including an inductor and a condenser and proportioned for resonance at said predetermined frequency, a loud speaker provided with a voice winding and a field winding, means to connect said resonant circuit and said voice winding in series across the output terminals of the demodulators to form a closed output circuit for the demodulator, a relay, means including a rectifier to connect a winding of the relay across a portion of said inductor to energize the relay as long as such signaling current is supplied to the demodulator, an indication circuit including an indicator and a front contact of the relay, and circuit means including said field winding and a back contact of the relay to condition the loud speaker for reproducing the speech of such telephone current supplied to the demodulator.

5. In combination, receiving equipment normally conditioned for reception of a signaling current of a predetermined single frequency or a telephone current of the voice frequency range, a resonant circuit including an inductor and a condenser and proportioned for resonance at said predetermined frequency, a loud speaker provided with a voice winding and a field winding, means for connecting said resonant circuit and said voice winding in series across the output terminals of said receiving equipment to form a closed output circuit, a relay, means including a rectifier to connect a winding of the relay across a portion of the inductor to energize the relay when current resulting from reception of the signaling current flows in the output circuit, an indication circuit including an indicator and a front contact of the relay to indicate reception of signaling current, and circuit means including said field winding and a back contact of the relay to condition the loud speaker when the signaling current ceases for reproducing the voice frequencies of the current flowing in the output circuit as a result of reception of the telephone current.

6. In combination, receiving equipment normally conditioned for reception of a signaling current of a predetermined single frequency or a telephone current of the voice frequency range, a resonant circuit including an inductor and a

condenser and proportioned for resonance at said predetermined frequency, a loud speaker provided with a voice winding and a field winding, means for connecting said resonant circuit and said voice 5 winding in series across the output terminals of said receiving equipment to form a closed output circuit, a relay, means including a rectifier to connect a winding of the relay across a portion of the inductor to energize the relay when 10 current resulting from reception of the signaling current flows in the output circuit, an indication circuit including an indicator and a front contact of the relay to indicate reception of signaling current, circuit means including said field winding 15 and a back contact of the relay to condition the loud speaker when the signaling current ceases for reproducing the voice frequencies of the current flowing in the output circuit as a result of reception of the telephone current, and means 20 for at times rendering said receiving equipment immune to current transmitted from the same station.

7. In combination, receiving equipment normally conditioned for reception of a signaling 25 current of a predetermined single frequency or a telephone current of the voice frequency range, a tuned circuit including an inductor and a condenser and tuned to resonance at said predetermined frequency, a loud speaker, a winding associated with said loud speaker for at times actuating the loud speaker, means to connect one terminal of the tuned circuit with one output terminal of said receiving equipment and to connect a mid terminal of the inductor with the 30 other output terminal of the receiving equipment over said winding to form a closed output circuit for the receiving equipment, a relay, means including a rectifier to connect a winding of the relay across a portion of said inductor to energize 35 said relay when current resulting from reception of said signaling current flows in said output circuit, an indicator circuit controlled by said relay when energized to indicate reception of signaling current, and circuit means controlled 40 by said relay when deenergized to condition said loud speaker as required for actuation of the loud speaker by the first mentioned winding when current resulting from reception of said telephone 45 current flows in said output circuit.

8. Receiving apparatus for communication systems comprising, a demodulator capable of demodulating a carrier telephone current and a signaling current equivalent to the carrier modulated by a predetermined frequency, a loud speaker provided with a voice coil and a field coil, a tuned circuit consisting of an inductor and a condenser and tuned to resonance at said predetermined frequency, an output circuit connected with the output terminals of said demodulator 55 and including said tuned circuit and said voice coil, a relay, means to connect a winding of the relay across a portion of said inductor to energize the relay when current of said predetermined frequency flows in said output circuit, an indication circuit including a front contact of the relay and an indicator as well as a current source to display an indication as long as such signaling current is supplied to the demodulator, and another circuit including a back 60 contact of the relay and said field coil as well as a current source to render the loud speaker responsive to the voice frequencies of current flowing in said output circuit when the signaling current ceases and said telephone current is supplied to the demodulator.

9. Receiving apparatus for communication systems comprising, a demodulator capable of demodulating a carrier telephone current and a signaling current equivalent to the carrier modulated by a predetermined frequency, a loud speaker, a tuned circuit consisting of an inductor and a condenser and tuned to resonance at said predetermined frequency, an output circuit connected with the output terminals of said demodulator and including said tuned circuit and a first winding 10 associated with the loud speaker in series, a relay, means to connect a winding of the relay across a portion of said inductor to energize the relay when current of said predetermined frequency flows in said output circuit in response to signaling current supplied to the demodulator, and circuit means including a back contact of the relay and a second winding associated with the loud speaker to condition the loud speaker when such signaling current ceases for reproduction of the voice frequencies of the current flowing in said first winding in response to telephone current supplied to the demodulator.

10. Receiving apparatus for communication systems comprising, a demodulator capable of demodulating a carrier telephone current and a signaling current equivalent to the carrier modulated by a predetermined frequency, a loud speaker, a tuned circuit consisting of an inductor and a condenser and tuned to resonance at said predetermined frequency, an output circuit connected with the output terminals of said demodulator and including said tuned circuit and a first winding associated with the loud speaker in series, a relay, means to connect a winding of the relay across a portion of said inductor to energize the relay when current of said predetermined frequency flows in said output circuit in response to signaling current supplied to the demodulator, an indication circuit including an indicator and a front contact of said relay to display an indication as long as signaling current is supplied to the demodulator, and other circuit means including a back contact of the relay and a second winding associated with the loud speaker to condition the loud speaker when such signaling ceases for reproduction of the voice frequencies of current flowing in said first winding in response to said telephone current supplied to the demodulator.

11. In combination, receiving equipment normally conditioned for reception of communication current and including a demodulator capable of demodulating a given telephone current and a signaling current of a predetermined frequency, a normally closed output circuit connected with said demodulator and including an inductor and a condenser arranged in parallel and in series with another winding, said inductor and condenser proportioned for resonance at the frequency corresponding to said signaling current when demodulated, a loud speaker operatively associated with said other winding but normally inactive, a relay, means including a rectifier to connect a winding of the relay across a portion of said inductor to energize the relay as long as signaling current is received, indication means controlled by said relay to indicate reception of the signaling current, and other means controlled by said relay to render said loud speaker active 65 and effective only when said relay is deenergized.

12. In combination, receiving equipment normally conditioned for reception of communication current and including a demodulator capable of demodulating a given telephone current and

a signaling current of a predetermined frequency, a normally closed output circuit connected with said demodulator and including an inductor and a condenser arranged in parallel and in series 5 with another winding, said inductor and condenser proportioned for resonance at the frequency corresponding to said signaling current when demodulated, a loud speaker operatively associated with said other winding but normally inactive, a relay, means including a rectifier to connect a winding of the relay across a portion

of said inductor to energize the relay as long as signaling current is received, indication means controlled by said relay and including a lamp to visually indicate reception of the signaling current and a bell to sound a warning when the 5 signaling current ceases, and other means controlled by said relay to render said loud speaker active and effective only when the relay is released.

WILLARD P. PLACE. 10
